UNITED STATES PATENT OFFICE

EDWIN EARL MOORE, OF GARY, INDIANA, ASSIGNOR TO AMERICAN SHEET AND TIN PLATE COMPANY, OF PITTSBURGH, PENNSYLVANIA, A CORPORATION OF NEW JERSEY

SHEARS

Application filed February 24, 1928. Serial No. 256,606.

This invention relates to shears and more particularly to a cutting-up shear for cutting up relatively long, thin metal strips into short lengths, and has for its object the provision of a shear of this class which will be automatic in operation and which may be readily adjusted so as to cut short lengths of equal weight regardless of the thickness of the strips.

10 The present shear is particularly adapted for use in a sheet mill in which the metal is first roughed down into long strips, and the strips are then cut up into short length sheets which are matched in pairs, doubled, then reheated and further reduced. In rolling or roughing down the bars or slabs to form the strips, some strips are elongated more than others due to the variations in the heat of the metal, therefore it is necessary to cut the sheets, formed from the shorter strips, shorter than the sheets cut from the longer strips, since it is essential to have the same, or as nearly the same, amount of metal in each sheet.

15 20 25

25 The present shear is so designed that it may be readily adjusted to cut sheets in proportion to the length of each strip.

In the drawings—

30 Figure 1 is a plan view of a shear embodying my invention.

Figure 2 is a side elevation thereof.

Figure 3 is a fragmentary side elevation on a large scale showing the shear-feed roller drive.

35 Figure 4 is a similar view partly in section.

Figure 5 is a sectional elevation taken on the line V—V of Figure 3.

40 Figure 6 is a sectional elevation taken on the line VI—VI of Figure 3.

Figure 7 is a detail elevation showing the ratchet-clutch for driving the feed rollers.

Figure 8 is a sectional elevation taken on the line VIII—VIII of Figure 7.

45 Figure 9 is a fragmentary elevation showing the feed roller drive pinions.

Referring more particularly to the drawings, the numeral 2 designates the shear housing. A lower stationary shear-blade

50 support 3 is secured between the sides of the

housing 2 and has a shear-blade 4 secured thereto. A reciprocating shear-head 5 is mounted in vertical guideways 6 in the housing and carries a shear-blade 7. The shear-head 5 is provided with trunnions 8 at each end on which one end of pitmans 9 are journaled. The other or lower ends of the pitmans 9 are fitted around eccentric disks 10 secured on a shear drive-shaft 12 which is journaled in the housing 2. The lower end of one of the pitmans 9 is slotted to form ears 13 and a connecting-rod 14 has one end mounted between the ears 13 on a pivot pin 15.

The other end of the rod 14 is pivotally connected to a pin 16 which carries blocks 17 slidably mounted in arcuate guide slots 18 in an inverted U-shaped block 19. The block 19 is supported vertically by a cam member 20 which is slidable longitudinally on the base of the shear housing and has a rearwardly and upwardly inclined cam slot 21 therein. The cam member 20 is of relatively narrow construction and is fitted between the side walls of the block 19 and a roller 22 journaled on an axle 23 carried by the block 19, which roller is mounted to ride in the cam slot 21 and supports the block.

An inverted U-shaped casting 24, which has its side walls sufficiently spaced to fit over the block 19 and cam member 20, is fitted over said members and pivotally mounted on the housing by pivot pins 24a. The upper face of the casting 24 is arcuate shaped and provided with teeth forming a segmented rack 25. The sides of the casting 24 are slotted to form guideways 25a to receive blocks 25b carried by the pin 16.

A shaft 26 is journaled in the housing 2 and carries a pinion 27 which meshes with the rack 25.

A plurality of feed-in pinch rollers 28 are journaled in the housing 2 to the rear of the shear-blades and are adapted to feed the strips to be sheared through the machine. The lower ones of the pinch rollers 28 are geared together by gears 29 so that all of said rollers will operate simultaneously. One of the rollers 28 is provided with an 100

extended shaft 30. A pawl-disk 31 is journaled for free rotation on the extended shaft 30 and said disk has an extended hub portion 32 on which is keyed a pinion 33 which is in mesh with a gear 34 carried by the shaft 26, so that when the shaft 26 is rotated by the segmental rack 25 and pinion 27, the pinion 33 and pawl-disk 31 will be rotated.

5 A ratchet-disk 35 is keyed on the extended shaft 30 and the pawl-disk 31 is provided with spring pressed pawl-fingers 36 which are adapted to engage the teeth 37 of the ratchet-disk 35 and rotate said disk and shaft 30 when the pawl-disk is rotated forwardly and to ride freely over said teeth when said pawl-disk is rotated rearwardly. The pawl-disk 31 and ratchet-disk 35 form, in effect, a one-way clutch and it will be understood that various other forms of one-way clutches may be substituted therefor.

10 The rotation of the extended shaft 30 will cause a simultaneous forward rotation of all the feed-in pinch rollers 28 since said rollers are all geared together as before stated.

15 The shear-head drive or operating shaft 25 is adapted to be operated by a motor 40. The armature shaft 41, of the motor 40, carries a pinion 42, which is in mesh with a gear 43 on a jack-shaft 44. The shaft 44 also carries a pinion 45 which is in mesh with a gear 46 journaled on the extended shaft 30 and meshed with a gear 47 on a second jack-shaft 48. The shaft 48 also carries a pinion 49 which meshes with a drive-gear 50 journaled on the drive-shaft 12 and adapted to drive said shaft through a clutch 51 of standard design.

20 The gear 46, which is free on the extended shaft 30, may be connected to said shaft to drive the feed-in rollers 28 by a standard clutch 52 when desired.

The shear thus far described is operated as follows:

25 Power will be applied by the motor 40 and the clutch 51 will be engaged to drive the shaft 12. Operation of the shaft 12 will reciprocate the shear-head 5 and upper shear-blade 7, through the eccentrically operated pitmans 9. As the connecting-rods 50 9 are operated by the eccentrics 10, their lower ends will be moved through an elliptical path which will cause a reciprocatory motion to be imparted to the connecting-rod 14 connected to the lower end of one of the pitmans 9, and to the rack casting 24 through the pin 16 and blocks 25^b mounted in the guideways 25^a. The reciprocatory movement of the connecting-rod 14 will thus be imparted to the rack casting 24 which will be rocked about its pivotal mounting pins 25. As the rack-casting 24 is rocked, its rack portion 25 will operate to rotate the pinion 27 and shaft 26 forward and backward. On each backward rotation of the shaft 26 the gear 34 on said shaft will

be rotated to drive the pinion 33 on the hub 32 of the pawl-disk 31, which will cause the pawl-disk 31 to rotate in a forward direction and engage the pawl-fingers 36 with the teeth 37 on the ratchet-disk 35 so as to 70 drive the feed-in pinch rollers in a forward direction and feed in the strip to be sheared a predetermined length.

This automatic strip feed will remain in operation as long as the clutch 51 remains 75 engaged to drive the shaft 12 which operates the shear-head. The clutch will be disengaged to stop the operation of the shear.

If, for any reason, it is desired to feed a 80 length of strip through the machine when the shear-head is stationary, the pinch rollers 28 may be operated by engaging the clutch 52.

The length of strip fed through the shear between each shearing operation may be 85 varied by changing the vertical position of the blocks 25^b, which form a connection between the connecting-rod 14, and the rack-casting 24. The vertical position of the blocks 25^b relative to the rack casting may 90 be varied by adjusting the cam 20 which carries the supporting block 19.

In order that the cam 20 may be adjusted to vary the length of strip fed through the machine at each shearing operation, in proportion to the total length of the strip, a novel tell-tale adjusting mechanism is provided.

The tell-tale adjusting mechanism comprises a shaft 60 which extends lengthwise of the bed on which the strips to be sheared are supported. The shaft 60 is journaled in suitable bearings 61 and is provided at a point intermediate its ends with a beveled pinion 62, which meshes with a beveled gear 63 on a shaft 64 journaled in a housing 65 and carrying a sprocket 66. A second beveled pinion 67 is mounted on the rear end of the shaft 60 and is meshed with a beveled gear 68 on a shaft 69 journaled in a housing 70 and carrying a sprocket 71. The sprockets 66 and 71 are connected by a tell-tale sprocket chain 72, which carries an indicator pointer 73.

10 The forward end of the shaft 60 is journaled in a housing 74 and is provided with a pinion 75 which is meshed with a gear 76 on a jack-shaft 77 journaled in the housing 74 and provided with a sprocket 78 which is connected to a sprocket 79 on a threaded shaft 80 by a chain 81. The shaft 80 is journaled in bearings 82 and 83 in the shear housing and has a threaded engagement with a nut 84 which has a fixed mounting in the cam 20.

11 The shaft 60 is adapted to be rotated by a reversing motor 85 which is connected to the shaft by a train of reducing gearing 86.

12 In operation, when a strip is to be sheared it is first drawn through the shear and its

forward end is cropped off. The motor 85 is then started to move the tell-tale indicator pointer 73 until it is directly opposite the rear end of the strip. As the shaft 60 is 5 rotated by the motor 85 to move the tell-tale indicator pointer the threaded shaft 80 will be rotated so as to shift the cam 20 through the nut 84.

The cam 20, screw-shaft 80, sprockets 78 10 and 79, gear 76 and pinion 75, pinions 62 and 67 and gears 63 and 68, and sprockets 66 and 71, are all so proportioned and arranged that the movement of the cam 20 will change the point of connection between 15 the connecting rod 14 and the rack 24 an amount which will cause the pinch rollers 28 to be rotated by the rack a greater or lesser amount, according to the direction the tell-tale indicator is moved, equal to 20 the result obtained by dividing the length of travel of the tell-tale indicator by the number of pieces arranged to be cut from each strip.

If it is desired to change the number of 25 pieces to be cut from the strips of metal, this change may be accomplished by changing the ratio between the pinion 75 and gear 76.

While one specific embodiment of this 30 invention has been described in detail, it will be understood that the invention is not limited thereto since various changes may be made without departing from the scope thereof as defined in the appended claims.

35 1. An automatic cutting-up shear for shearing strips into a plurality of short lengths of equal weight, comprising a shear-head, means for operating said shear-head, a plurality of feed-in rolls for feeding the 40 strip to be sheared through said shear-head in a step-by-step manner, means for operating said feed-in rolls, means for limiting the amount of movement of said feed-in rolls, and means for adjusting said last named 45 means including a tell-tale chain and pointer adapted to be moved up to the rear end of the strip and means connected with said tell-tale chain and pointer adapted to move said limiting means a distance equal to the 50 length of movement of the tell-tale pointer divided by the number of short lengths to be cut.

55 2. An automatic cutting-up shear for shearing strips into a plurality of short lengths of equal weight, comprising a shear-head, means for operating said shear-head, a plurality of feed-in rolls for feeding the strip to be sheared through said shear-head in a step-by-step manner, means operable 60 by said shear-head operating means for operating said feed-in rolls, means independent of said last named means for operating said feed-in rolls independently of said shear-head, means associated and cooperating with said feed roll operating means

operable by said shear-head for limiting the amount of movement of said feed-in rolls, and means for adjusting said last named means including a tell-tale chain and pointer adapted to be moved up to the rear 70 end of the strip and means connected with said tell-tale chain and pointer adapted to move said limiting means a distance equal to the length of movement of the tell-tale pointer divided by the number of short 75 lengths to be cut.

3. An automatic cutting-up shear for shearing strips into a plurality of short lengths of equal weight, comprising a shear-head, means for operating said shear-head, a plurality of feed-in rolls for feeding the strip to be sheared through said shear-head in a step-by-step manner, means operable by said shear-head operating means for operating said feed-in rolls, means for limiting the amount of movement of said feed-in rolls, and means for adjusting said last named means including a tell-tale chain and pointer adapted to be moved up to the rear 80 end of the strip and means connected with 85 said tell-tale chain and pointer adapted to move said limiting means a distance equal to the length of movement of the tell-tale pointer divided by the number of short 90 lengths to be cut.

4. An automatic cutting-up shear for shearing strips into a plurality of short lengths of equal weight, comprising a shear-head, a frame supporting said shear head, means for reciprocating said shear-head including a power shaft, an eccentric on said shaft and a pitman connecting said eccentric and said shear-head, a plurality of feed rollers for feeding the strip to be sheared through said shear-head in a step-by-step manner, all of said rollers being geared together, driving means for said rollers including a shaft, a pinion on said shaft, a one-way clutch connecting said shaft and said rollers, a segmental rack in mesh with said pinion and having a pivotal mounting on said frame, a connecting-rod having a fixed point of connection at one end with said shear operating pitman and having its other end connected to a bearing mounted in a vertical slot in said rack, a block for limiting the vertical position of said bearing in said slot, a cam for varying the vertical position of said block so as to vary the vertical position of said bearing and thereby vary the throw of said rack, and means for adjusting said cam so as to change the vertical position of said block including a tell-tale chain and pointer adapted to be moved up to the rear end of the strip to be cut and means connected with said tell-tale chain and pointer adapted to move said cam a distance sufficient to change the throw of said rack so that said rollers will be fed forward either a greater or lesser distance at each 110

115

120

125

130

said shear operating pitman and having its other end connected to a bearing mounted in a vertical slot in said rack, a vertically adjustable block for limiting the vertical position of said bearing in said slot, an adjustable cam member for supporting said block, and means for adjusting said cam, said means including a nut carried by said cam, a threaded shaft in threaded engagement with said nut, a member adapted to be moved up to the rear end of the strip to be cut, and means operable by the movement of said member adapted to rotate said threaded shaft and move said cam a distance sufficient to change the vertical position of said block and said bearing and thereby change the throw of said rack so that said feed rollers will be fed forward either a greater or lesser distance at each throw of said rack equal to the length of movement of said member divided by the number of short lengths to be cut.

9. In a shearing machine, shear means, feed means, a drive for the feed means including a variable ratio means, gauge means adjustable to different positions depending on the length of a piece of material to be sheared, and a connection between the gauge means and the variable ratio means effective for adjusting the variable ratio means.

10. In a shearing machine, shear means, feed means, a reciprocable driver for the feed means, a variable ratio means, a driving connection between the reciprocable driver and the variable ratio means, gauge means adjustable to different positions depending on the length of a piece of material to be sheared, and a connection between the gauge means and the variable ratio means effective for adjusting the variable ratio means.

In testimony whereof, I have hereunto set my hand.

EDWIN EARL MOORE.
